UNITED STATES PATENT OFFICE.

HARRY A. ROSS, OF PITTSBURGH, AND OTTO KOEHLER, OF JEANNETTE, PENNSYLVANIA, ASSIGNORS TO PITTSBURGH LAMP, BRASS & GLASS COMPANY, OF PITTSBURGH, PENNSYLVANIA, A CORPORATION OF NEW JERSEY.

DESIGN FOR A BOWL FOR LIGHTING FIXTURES.

61,350.

Specification for Design.

Patented Aug. 8, 1922.

Application filed November 8, 1921. Serial No. 513,819. Term of patent 7 years.

To all whom it may concern:

Be it known that we, HARRY A. Ross and OTTO KOEHLER, citizens of the United States, residing at Pittsburgh, county of Allegheny, State of Pennsylvania, and Jeannette, county of Westmoreland, State of Pennsylvania, respectively, have invented a new, original, and ornamental Design for a Bowl for Lighting Fixtures, of which the following is a specification, reference being had to the accompanying drawings, forming part thereof.

Fig. 1 is a bottom view showing our new design; and

Figs. 2 and 3 are side elevational views thereof.

We claim:

The ornamental design for a bowl for lighting fixtures, as shown.
